UNITED STATES PATENT OFFICE

JOHN FREDRIK HALSTEAD, OF BROOKLYN, NEW YORK, ASSIGNOR TO INTERNATIONAL CIGAR MACHINERY COMPANY, A CORPORATION OF NEW JERSEY

WRAPPER PATCHING DEVICE FOR CIGAR MACHINES

Application filed January 20, 1931. Serial No. 510,034.

This invention relates to wrapper patching devices for cigar machines, its main object being to provide means for applying a finishing patch to the head end or tip of a cigar, this patch to be cut from the same leaf as the wrapper of each individual cigar and as near as possible to the portion forming the head end of the cigar when the wrapper has been applied to it. With this and other objects not specifically mentioned in view, the invention consists in certain constructions and combinations which will be hereinafter fully described and then specifically set forth in the claims hereunto appended.

In applying cigar wrappers by machine, the head of the cigar is finished by a small conical wheel having a suitable cone angle and set at such an angle to the axis of the cigar as best fits the desired shape of its head. Since the wrapper lies flat on the carrier which transfers it from the cutting bed to the wrapper applying device, it is fed to the circumference of the cigar bunch in a straight line which is parallel to its axis along the cylindrical portion of the bunch and becomes a tangent to the bunch when engaging with the aforesaid conic heading wheel. The straight contour of the wrapping wheel and the curved contour of the cigar shape at the apex of the head can never be identical, the divergence of the tangential straight line from the actual cigar shape being the greater the more blunt the head of the cigar is desired to be. Within the range of this more or less great divergence at the apex of the cigar, the wrapper will form wrinkles which give the cigar an unsightly appearance, especially objectionable when the cigars are to be packed with their ends up in tin cans or similar containers.

To hide the aforesaid wrinkles and thus to give the cigar end a neat appearance, a small patch is placed at the apex of the cigar head, and in order to fulfill its purpose completely, this patch must be of the same texture and color as the surrounding portions of the wrapper. It thus becomes necessary to cut this patch not only from the same leaf as the wrapper used on each individual cigar, but

also from the same portion of that leaf which is to form the head end of the cigar.

In order to attain this object, the wrapper cutting bed of the cigar machine is equipped near its head end with an additional small die which at each cutting stroke cuts from the wrapper leaf a small octagonal patch which is moved up into delivery position by a suction-headed patch plunger attached to the lifting rod of the suction head of the main wrapper die. The polygonal form of the patch is preferable to the circular form, because the straight sides and sharp corners of the former blend better with the veins of the tobacco than would the continuously curved contour of a round patch which would appear as a circular incision around the tip of the cigar. The patch then is taken from the patch plunger by a patch carrier arm so synchronized with the cigar machine that it arrives at the patch delivery station at the same time as the cigar to which that wrapper is applied from which the patch has been cut. Since there are a number of cigars undergoing different operations in the machine at the same time, several finished cigars will be ejected by the machine during the interval from the cutting of a wrapper to its delivery on a cigar; it is therefore necessary to provide a number of patch transfer arms identical with the number of cigars ejected during this interval. These arms are arranged in symmetrical star formation on an intermittently revolving tube connected with the suction apparatus of the cigar machine. In order to prevent interference with the hands of the operator serving the wrapper die, the arms of the patch carrier are so disposed and their intermittent motion is so arranged that each arm when approaching its patch receiving position dwells for the greatest possible length of time at the greatest possible distance from the same, so as to leave maximum clearance for the manipulation of the wrapper.

The patch is applied by pushing the cigar against the same manually as it arrives in delivery position in which the suction head of the delivery arm is in alignment with a stand or guide into which the newly delivered cigar is placed and along which it is pressed

against the patch. The cigar coming fresh from the wrapping device, its tip has enough surplus paste from sealing the flag so that no further paste is required for applying the 5 patch. During and shortly after their dwell in the patch receiving position, the patch transfer arms receive strong intermittent suction from one source to lift the patch from the die and to transfer it to the suction head 10 of the arm. After the arm has traversed a small angle, its head is subjected to a moderate continuous suction from another source which remains on the patch until it is cut off by the pressure of the cigar against the 15 patch pushing the movable patch holder against a spring in the suction head, thereby displacing the suction opening of the head with respect to the suction duct in the arm.

In the accompanying drawings which form 20 a part of this specification and in which like characters of reference indicate the same or like parts:

Fig. 1 is a view showing the usual manner of applying the flag of the wrapper to the 25 head end of a cigar;

Fig. 2 is a side perspective view showing a finished cigar with a patch applied to its tip;

Fig. 3 is a side elevation of the improved 30 wrapper patching device;

Fig. 4 is an end elevation of the same;

Fig. 5 is a sectional view on enlarged scale taken on the line 5—5 of Fig. 4; and

Fig. 6 is a partial plan view of Fig. 3 showing 35 the relative position of the wrapper die and patch cutting die.

In carrying the invention into effect, there is provided means for cutting a patch for a cigar wrapper and means for removing the patch therefrom and carrying it into position 40 for application to the wrapper. In the best forms of construction contemplated, the patch cutting means includes a patch cutting die and a patch plunger within said die and connected to a suitable source of suction for retaining the tobacco leaf on the die in position to be cut. In the preferred forms of construction, the patch transfer means includes a plurality of transfer arms on a hub which is rotated from an indexing mechanism 45 and connected to a source of strong suction and a source of weak suction. The transfer arms carry patch carriers which are connected to the sources of suction through said arms and hub, whereby strong suction may be applied to the carriers to remove the patch which is then retained by the weak suction. These various means and parts may be widely varied in construction within the scope of 50 the claims, for the particular device selected to illustrate the invention is but one of many possible concrete embodiments of the same. The invention, therefore, is not to be restricted to the specific construction shown and described.

65 Referring to Fig. 1, the head of the cigar

bunch C, when having its wrapper W applied in the wrapping device is in contact with a conical heading wheel H, placed at an angle most suitable to the shape of the cigar. At 70 the cigar tip, the contour of the cigar diverges from the conic surface of wheel H, leaving a space A at the apex of the cigar in which the flag F of the wrapper is not held tightly against the bunch by the heading wheel and in which therefore, the wrapper will wrinkle to a greater or less extent. To cover up these wrinkles, a patch P is applied to the cigar 75 end, giving the finished cigar the appearance shown in Fig. 2.

Referring to Figs. 3 to 6, the wrapper die plate holder 10, which is supported by the frame of the cigar machine, carries the die plate 11 on which is mounted the die shell 12 surrounding the suction head 13. The hub 14 of the die plate holder 10 carries bushings 15 in which is slidably mounted a vertical rod 16 connected to the suction head 13. Attached to rod 16 is an arm 17 to which is fastened a rod 18 the upper end of which carries the octagonal patch plunger 19. The rod 18 is 80 slidably guided in the sleeve 20 which has a shoulder 21 whereby it is fastened to the die plate 11. The patch cutting die 22 is mounted on springs 23 carried by studs 24 and is counterbored to fit the diameter of the sleeve 20 85 on which it rests.

The hollow patch transfer arms 25 carried by tubular hub 26 are driven by means of sprockets 27 and 28 connected by chain 29, the sprocket 27 being attached to the hub 26 and the sprocket 28 being mounted on shaft 30 which has fixed thereon the indexing wheel 31 and the lock plate 32. The cam 33 which is driven from the main drive of the cigar machine carries a plate 34 to which are fastened driving pins 35 and 36, the cam on revolving bringing the said driving pins into engagement with indexing wheel 31 and in this manner intermittently revolving the arms 25.

The operation of the device is as follows: The operator of the cigar machine, when placing a wrapper leaf W on the suction head 13, thereby also covers the patch cutting die 22, the suction applied through pipe 37 holding the leaf firmly on the head while the cutter rollers, not shown, roll over the dies and cut the wrapper and patch from the leaf. To provide suction to the patch plunger 19, a hole 38 in the sleeve 20 registers with a slot 39 in the die plate 11 which is connected to the pipe 37, while the rod 18 which is partially hollowed out has a vertical slot 40 in alignment with the suction hole 38. Upon the completion of the cutting operation, the patch transfer arms 25 are turned through an angle of 75 degrees by the operation of the indexing device described above, the lowermost arm moving into the dotted position 25', arriving there shortly before the suction head 130

13 and patch plunger 19 which are lifted by the motion of rod 16 reach their upper positions 13' and 19'. The suction head and patch plunger having reached their upper positions, the suction in them is automatically shut off and suction from a strong intermittent source is applied to the wrapper transfer T. The wrapper W in this manner is transferred to the carrier T which carries it to the wrapper applying mechanism of the cigar machine.

The sprocket 27, as shown in Fig. 5, has a number of holes 41 corresponding to the number of arms 25 and communicating with slots 54 in the hub of sprockets which lead to the patch carriers as hereinafter described. The arm 25 when it reaches the position 25', stops momentarily with one of the holes 41 directly in alignment with the suction hole 42 in the support bar 43 leading to a flexible pipe 42a connected to a source of strong suction. In this manner a strong suction reaches the perforated patch carrier 44 through the hole 45 of arm 25 thereby transferring the patch P from the plunger 19 to the patch carrier 44. The patch carriers 44 are movably fitted into heads 46 carried by the arms 25 and pressed outwardly against a shoulder therein by springs 47 which are seated in recessed screws 48 to bring the suction spring of the patch carrier into register with the bores of the head and transfer arm. The patch plunger 19 is then lowered together with the suction head and the arm 25' with the patch P is now moved through an angle of 45 degrees to the position 25' by the indexing device described above and the hole 41 leaves the suction hole 42, while a moderate continuous suction is applied to the patch through a flexible pipe 49 connected to a suction pump not shown. The pipe 49 is fitted into the bore 50 of an enlarged portion of the shaft 51 which has a number of holes 52. The hub 53 of sprocket 27 has slots 54 provided with ducts 55 which register with the holes 52 of shaft 51. The suction passes through the slots 54 to the holes 45 of the arms 25, the shaft 51 carrying the plug 56 which holds the shaft in alignment and also keeps the suction passage air tight. Since the number of arms 25 corresponds to the number of cigars ejected by the machine during the time of their wrapping and finishing operations, each patch P arrives at stand 57 at the same moment when the cigar C having the wrapper W cut from the same leaf is ejected from the wrapping mechanism and placed in the stand. As the cigar has just been delivered from the machine, its tip still has a surplus quantity of moist paste deposited on it, therefore when the suction is shut off by pushing the patch carrier into the head 44, to close the end of the hole 45, the patch sticks to the cigar without further application of paste.

The cam 33 on revolving brings the driv-

ing pin 35 into engagement with the indexing wheel 31, but the pin 35 before it can drive the mechanism must first release a locking device. This is accomplished by the pin 35 engaging with the bevel 58 of the sliding plate 59 on the rods 60 carried by the support 43, the plate 59 carrying a stop pin 61 which engages with the cutouts 62 of the locking plate 32. When the plate 59 moves outward, it takes along the pin 61, and the indexing wheel is then free to be turned by the pin 35. The wheel 31, through shaft 30, rotates the sprocket 28 which through the chain 29 turns the sprocket 27. When one of the arms 25 reaches position 25', the springs 63 on the rods 60 push the plate 59 back to its locked position. The driving pin 38 then comes into engagement with the bevel 58 and releases the locking device in the above described manner and drives the indexing wheel 31. The pin 36 has a projection 64 which fits into the space 65 between the teeth of the indexing wheel. The projection 64 is a safeguard for the timing of the arms 25 as it prevents their turning relative to the indexing wheel and driving pins when handling the arm star.

What is claimed is:

1. In a wrapper patching device for cigar machines, the combination with means for cutting a patch for a wrapper, of mechanism for removing the patch from said means and carrying it into position for application to the wrapper. 95

2. In a wrapper patching device for cigar machines, the combination with means for cutting a patch for a wrapper, of mechanism for removing the patch from said means and carrying it into position for application to the wrapper, said means including a patch cutting die, a patch plunger slidably mounted within said die and adapted to retain a tobacco leaf in position to be cut on said die and to carry the patch cut from the leaf to a position where it is removed by said mechanism. 100

3. In a wrapper patching device for cigar machines, the combination with means for cutting a patch for a wrapper, of mechanism for removing the patch from said means and carrying it into position for application to the wrapper, said means including a die shell, a wrapper suction head and a patch cutting die mounted in said shell, a patch plunger mounted to reciprocate within said die, and operative connections for applying suction to said head and plunger to hold a tobacco leaf in place to permit a wrapper and a patch to be cut therefrom. 115

4. In a wrapper patching device for cigar machines, the combination with means for cutting a patch for a wrapper, of mechanism for removing the patch from said means and carrying it into position for application to the wrapper, said means including a patch 125

- transfer arm, a patch carrier mounted in said arm, means for moving said arm into position to remove the patch from said means and carry it into position for application to 5 a wrapper, and operative connections for applying a relatively strong suction and a relatively weak suction to said patch carrier, whereby the strong suction may remove the patch from said means and the weak suction 10 may retain the patch on said patch carrier.
5. In a wrapper patching device for cigar machines, the combination with means for cutting a patch for a wrapper, of mechanism for removing the patch from said means 15 and carrying it into position for application to the wrapper, said mechanism including a rotatable hub, a plurality of patch transfer arms mounted on said hub, a sprocket connected to said hub, and an indexing device 20 for driving said sprocket, said device including a shaft, a sprocket fixed to said shaft and connected to said first named sprocket, an indexing wheel and a lock plate fixed on said shaft, a locking device engaging said plate 25 to prevent rotation of said shaft, and cam means for rendering said locking device inoperative and rotating said indexing wheel.
6. In a wrapper patching device for cigar machines, the combination with means for 30 cutting a patch for a wrapper, of mechanism for removing the patch from said means and carrying it into position for application to the wrapper, said mechanism including a hollow transfer arm, a hollow head mounted 35 on one end of said arm, and a perforated patch carrier yieldingly mounted in said head and having a suction opening normally in registry with the bore of the head and transfer arm, said transfer arm being connected to a source of suction whereby the 40 suction to the patch carrier may be cut off by pushing it inwardly into the head.
7. In a wrapper patching device for cigar machines, the combination with means for 45 cutting a patch for a wrapper, of mechanism for removing the patch from said means and carrying it into position for application to the wrapper, said mechanism including a tubular hub, hollow transfer arms mounted 50 on said hub and having their bores leading to the bore of said hub, patch carriers mounted in said arms, a sprocket connected to said tubular hub and being provided with a hole and having a hub provided with slots 55 extending from said holes to the bores of said arms, a shaft having a hollow enlarged portion within the hub of said sprocket and provided with holes, ducts in the hub of said sprocket registering with the holes in said 60 shaft and leading to said slots, and suction pipes leading to the bore in said shaft and to the hole in said sprocket.
8. Means for cutting a patch for wrappers, 65 comprising a patch cutting die, and a patch plunger slidably mounted within said die and

adapted to retain a tobacco leaf in position to be cut on said die and to carry the patch cut from the leaf to a position where it may be removed.

9. Means for cutting a patch for wrappers, 70 comprising a die shell, a wrapper suction head and a patch cutting die mounted in said shell, a patch plunger mounted to reciprocate within said die, and operative connections for applying suction to said suction 75 head and plunger to hold a tobacco leaf in place to permit a wrapper and a patch to be cut therefrom.

10. Means for transferring a patch into 80 position for application to a wrapper, comprising a patch transfer arm, a patch carrier mounted in said arm, mechanism for moving said arm to carry the patch to a position where it may be applied to the tip of a cigar, and operative connections for applying suction to said patch carrier, whereby the patch may be retained on said patch carrier.

11. An indexing device, comprising a 85 shaft, an indexing wheel and a lock plate fixed on said shaft, a locking device engaging said plate to prevent rotation of said shaft, and cam means for rendering said locking device inoperative and rotating said indexing wheel.

12. In a cigar machine, the combination with a support for a tobacco leaf, of means 90 coacting with said support to cut a cigar wrapper from said leaf, and means cooperating with said wrapper cutting means to 100 cut a separate patch for said wrapper from the same leaf.

13. In a cigar machine, the combination with a support for a tobacco leaf, of means 105 coacting with said support for cutting a cigar wrapper having a portion for wrapping the cigar head, and means adjacent the cigar head wrapping portion of said wrapper, for cutting a head patch from the said leaf of substantially the same coloring as the head 110 portion of the wrapper.

14. The method of making cigars having 115 patches matching in color the color of the patched portion of the wrapper which consists in cutting the wrapper from a tobacco leaf, and cutting a patch from the remainder of the same leaf at a location close to the particular portion of the wrapper to be patched.

In testimony whereof, I have signed my 120 name to this specification.

JOHN FREDRIK HALSTEAD.
